(57) **CLAIM**

The ornamental design for a shell for an air compressor, as shown and described.

DESCRIPTION

FIG. 1 is a perspective view of the shell for an air compressor showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plain view thereof;

FIG. 7 is a bottom plain view thereof;

FIG. 8 is an exploded side plane view thereof; and,

FIG. 9 is a referential side plane view of the shell for an air compressor covering a control device mounted on an air tank of the air compressor, wherein the broken lines are shown for illustrative purposes and form no part of the claimed design.
